UNITED STATES PATENT OFFICE.

EDWIN JONES, OF PADESWOOD, NEAR MOLD, ENGLAND, ASSIGNOR OF ONE-HALF TO JOHN ARTHUR STUART, OF PRESTATYN, ENGLAND.

BRAKE FOR TRAMWAY AND RAILWAY VEHICLES.

No. 913,825.

Specification of Letters Patent.

Patented March 2, 1909.

Application filed March 23, 1908. Serial No. 422,847.

To all whom it may concern:

Be it known that I, EDWIN JONES, a subject of Great Britain, residing at Station House, Padeswood, near Mold, in the county of Flint, Wales, have invented new and useful Improvements in and Connected with Brakes for Tramway and Railway Vehicles, of which the following is a specification.

This invention has reference to brakes, for 10 use in connection with tramway and railway vehicles, and has for its object to provide a brake block or shoe and holder, which are simple in construction and efficient in use.

According to my invention, the back of a 15 brake block or shoe of the type commonly employed is provided at or about the ends with recessed or overhanging projections or lugs, and at the middle a projection or lug,— which is wider at its extremity than at its 20 base—is also provided.

The face of the holder is provided with a 25 cavity or recess similar in contour to that of the middle lug or projection referred to, and the ends or extremities of said holder are so formed as to be adapted to enter the recesses of the upper and lower lugs or projections referred to. The upper and lower lugs or projections on the block or shoe are slotted, and a hole or passage is provided in the middle 30 lug; the face of the holder is also suitably slotted; and when the block or shoe and holder are assembled they are temporarily pinned together by means of a suitable key or cotter.

35 The brake block or shoe is placed in position, in dovetail fashion from either side of the holder, and is removable from either side.

The function of the key or cotter referred to is only to prevent lateral displacement of 40 the brake block or shoe in relation to the holder, as the interfitting or dovetailed attachment of the shoe with the holder prevents vertical displacement. By removing said key or cotter the brake block may be 45 readily withdrawn from either side of the holder, and as said block is neither "right" nor "left," if, in use, the blocks or shoes of a vehicle should wear unequally, they may be readily interchanged with their holders.

50 Further, due to the manner in which the block or shoe is attached to the holder, should a portion of a block or shoe break when in use, the remaining part is maintained in position in the holder, and will not fall therefrom.

A drawing illustrating my invention is annexed hereto, in which:—

Figure 1 represents, in side elevation, the brake block and holder assembled. Fig. 2 is a view of the back of the block, and Fig. 3 60 is a plan view of same. Fig. 4 is a plan; and Fig. 5 is a view of the engaging face of the holder. Fig. 6 is a detached view of the key or cotter.

a represents generally the brake block, and 65 *b* the holder.

c are the upper and lower recessed or overhanging projections disposed at the back of block *a*.

d is the projection or lug at the middle of 70 block *a*, this being wider at its extremity than at its base, and *e* is the cavity in the holder *b* which is similar in contour to that of said lug *d*. When the block is placed in engagement with the holder, the ends or recesses *b*¹ of holder enter the recesses *c*¹ of projections *c*. 75

f indicates the slot dividing lugs *c*, and *g* is the hole provided in lug *d*; *h* is the slotted portion of the holder, to permit passage of 80 the key.

i is the key or cotter, which, when the brake block and holder are assembled, is passed through slots *f* and *h*, and hole *g*, to prevent lateral displacement of the brake 85 block in relation to the holder.

It will be obvious that holders of various types may be formed or provided with a block engaging face according to this invention.

Having now described my invention, what 90 I claim as new, and desire to secure by Letters Patent is:—

1. In brakes for tramway and railway vehicles, an interchangeable brake block and 95 holder comprising in combination a brake block having a lug in the middle, overhanging lugs or projections at or about the extremities; a holder, a recess in said holder adapted to receive said middle lug, and ends 100 adapted to fit into the recessed portions of the upper and lower lugs of the block; and a key adapted to prevent lateral displacement of the block relative to the holder.

2. In brakes for tramway and railway vehicles, an interchangeable brake block and 105 holder comprising a brake block having a lug in the middle which is wider (in side view) at its end than at its base, overhanging lugs at the extremities; a holder provided 110

with a recess adapted to receive said middle lug and ends adapted to fit into the recessed portions of said upper and lower lugs of the block; and a key adapted to pass between 5 said upper and lower overhanging lugs and through said middle lug.

In testimony whereof I have signed my

name to this specification in the presence of two subscribing witnesses.

EDWIN JONES.
